(57) **CLAIM**

An ornamental design for a radio control device for hobby models, as shown and described.

DESCRIPTION

FIG. 1 is a front view of a radio control device for hobby models;

FIG. 2 is a rear view of FIG. 1;

FIG. 3 is a top view of FIG. 1;

FIG. 4 is a bottom view of FIG. 1;

FIG. 5 is a right side view of FIG. 1;

FIG. 6 is a left side view of FIG. 1;

FIG. 7 is a perspective view of FIG. 1 showing the front, top, and left sides; and,

FIG. 8 is a perspective view of FIG. 1 showing the rear, top, and right sides.

The broken line showing of the remote control for hobby models is for the purpose of illustrating portions of the article that form no part of the claimed design.
